UNITED STATES PATENT OFFICE.

JOHN W. RHODES, OF HAVANA, ILLINOIS.

GRAIN-DRILL.

SPECIFICATION forming part of Letters Patent No. 433,086, dated July 29, 1890.

Application filed June 20, 1889. Serial No. 314,962. (No model.)

To all whom it may concern:

Be it known that I, JOHN W. RHODES, of Havana, in the county of Mason and State of Illinois, have invented certain new and useful

5 Improvements in Grain-Drills, of which the following is a specification, made with sufficient fullness, clearness, and exactness to enable others skilled in the art to which it relates to make and use the same.

10 This invention relates more particularly to press-drills—*i. e.*, drills the runners or furrow-openers of which are followed by wheels that press the soil over the grain, though the details are in great part applicable to other 15 classes of drills.

The invention consists in certain details of construction and combinations of parts relating to the runners, the runner-raising mechanism, the depressing-springs for the runners 20 and means for regulating the same, the neck-yoke, the evener, the hopper-lid lock, the fertilizer-conveyer, and the means for distributing the weight of the driver among the wheel-frames while permitting a limited amount of 25 lateral motion therein, all as hereinafter set forth in detail and specifically claimed.

In the drawings accompanying and forming a part of this specification, Figure 1 is a side view of the operative parts of a drill embodying my improvements. Fig. 2 is a side view of the runner-raising mechanism. Fig. 3 is an enlarged rear elevation of the latch that forms a part of the runner-raising mechanism. Fig. 4 is a side elevation of a runner 35 and a fertilizer-conveyer. Fig. 5 is a plan projected from Fig. 4, showing the connection of a runner with a cross-bar of a runner-frame and the spring used to impart yielding pressure to the runner. Fig. 6 is a sectional view

40 on broken line *x* in Fig. 5. Fig. 7 is a side view of the hopper-lid fastener. Fig. 8 is a plan of the same. Fig. 9 is a plan of a complete drill, with the tongue broken to expose certain peculiarities in the construction of the 45 evener. Fig. 10 is a side view of the front end of the tongue, showing the connection of the neck-yoke therewith. Fig. 11 is a projection from Fig. 1, showing the manner of forming the adjustable connection between the runner-shank and the fertilizer-conveyer. Fig. 50 12 is a rear view of the wheel-frames and wheels, showing the means employed to dis-

tribute the weight of the driver among the frames while permitting a limited amount of lateral motion therein. Fig. 13 is a perspective view of a runner detached from the shank. Fig. 14 is a diagram showing the construction of a runner as viewed from the rear, and also showing the condition of the ground when acted on by such runners and previous to the 60 covering action of the following wheels.

The drill comprises a forward frame 11, to which the tongue, the evener, the runners, the fertilizer-conveyer, and the hoppers for the seed and fertilizer are attached, and rear frames 12, pivotally connected with the forward frame, mounted on covering-wheels, and carrying the driver's seat and the runner-raising mechanism. The runners 1 are bifurcated at their forward terminations 1^a, and they embrace the projecting lugs 29 of a bracket secured to the front bar of the front frame. The rear end of the runner is composed of two parts 1^c, somewhat widely divergent at their terminations, and having the notches 1^d and the oblique edges 1^e. Through each bifurcated end of a runner and through the lugs 29 of each bracket extends a short shaft 34. On each shaft is a sleeve 33, and on each sleeve is a compound spiral spring 80 comprising the ends 30, which bear against the brackets, the coils 31, which encircle the sleeves, and the loop-terminations 32, which bear in the crotches of the runners. In the crotch of each runner is a small projecting 85 plate, (seen clearly at 1^b in Fig. 6,) and through each plate extends a set-screw 6. The ends of the loops of the springs rest in line with the ends of the screws, and the tension of the springs may be regulated by adjusting the 90 screws in the plates.

A bar 13 has the pivotal extension 13^a, that connects with the forward frame, and the rear extension 13^b, that carries the seat 28. It is supported from the rear of the frames 12 by 95 suitable braces 68, or in any other suitable manner. Bars 14 and 15 are carried by bar 13, and at their conjunction provide a pivotal bearing for segmental rack 16 and hand lock-lever 26. The beam 20 is located centrally among the runners, to the frame of which it is securely attached, and it carries the metal bar 19, which extends past the axles of the wheels. Lift-bar or link 18 connects

pivoted with the rear end of the bar 19 and extends upwardly. Arm 17 of rack 16 connects pivotally with the lift-bar at a point somewhat below its upper end, leaving an extension 18^a projecting above the pivot. Bracket 21 is secured to the rear of bars 15 by means of hook-bolts 27, 27 and 27^a, as seen in Fig. 3. A latch 23 pivots on a boss, through which bolt 27^a passes and swings in position to engage the recesses of rack 16. Strap 22 is held by the attaching-bolts 27, 27. It forms a guide for the latch and it extends obliquely upward and forms a point of connection for spring 24, which holds the latch normally out of contact with the rack.

The evener comprises the bars 48 and 48^a, secured to the front frame on opposite sides and equidistant from the center thereof, the three-horse eveners 49 and 49^a, connected one with bar 48 and the other with bar 48^a, the chain 50, extending around a pulley and connecting the long ends of the eveners together, the straps 51 and 51^a on the short ends of the eveners, and the doubletrees 52, 52^a, and 52^b, each provided with singletrees. The doubletree 52 connects with strap 51, doubletree 52^a is connected with the pulley around which the chain passes, and 52^b is connected with strap 51^a.

The seed-hopper fastener comprises the plate 41, secured to the inside of the hopper by means of the downward-projecting lugs 42. An upward-projecting ledge 43 has the slot 45, (seen only in Fig. 8,) and it has an extension that carries pivot-pin 35. An extended boss or short pin 38 provides a pivot for the lock-lever 37, and a lug 44 provides a point of connection for spring 40. Hinge-strap 10 is secured to the lid of the hopper, and it pivots on pin 35. It is provided with recesses, as 36, adapted to the lock-lever. The lugs 39 provide means for connecting lines 47 with the lock-lever, and the bifurcate end 41 of said lever provides a bearing for the operative end of spring 40. The lines 47 extend to the ends of the hopper, as indicated by dotted lines in Fig. 9, and connect with knobs 61, or are made otherwise accessible from the ends of the hopper. The pivot 35 acts with the other hinges of the hopper-lid, and when it is desired to open or close the same a line 47 is manipulated from an end of the hopper, thereby drawing the lock-lever from contact with a catch of the hinge-plate 10. After the lid is placed in the desired position the lock-lever is thrown into place by the spring and the lid is automatically locked open or closed, as the case may be.

The fertilizer-conveyer comprises a tubular chute 3, provided with a lug 3^a, that is connected with a lug 2^a on shank 2 by means of a bolt 46, that extends through both lugs and secures them together in various positions of adjustment by frictional pressure. The neck-yoke frame 56 is rigidly secured to the under side of the forward end of the tongue 53 by bolts 57. The swinging frame 58 has vertical

trunnions 59, that bear in the rigid frame. The main yoke 54 is pivoted in swinging frame 58 on the horizontal pin 60, and the secondary yokes 55 and 55^a are suitably secured to the ends of the main yoke. The frames extend downward sufficiently to enable the different connections to be made with the breast-straps without lowering the tongue to an undesirable extent, and the free swing of the main yoke on the different pivots tends to avoid breakage. The shanks of the runners have each a lug 4, over which a link of chain 5 passes. The chain is secured to a bar of the front frame, and is held on the lug by the removable pin 48. This connects the rear ends of the runners with the frame and enables some of the runners to be raised to conform to elevations, as dead furrows, extending lengthwise of the field.

A principal weight-distributing bar is shown at 62 in Fig. 12, and secondary bars are shown at 63 and 63^a. Bar 63 is connected at its ends with frames 12 by means of pins that extend through slots 64 in said frames 12. This bar, as well as bar 63^a, is preferably in duplicate, and it embraces the frames and the principal bar 62 in a manner to form well-balanced connections. Bar 63^a is trunnioned at its ends on blocks 64^a, and the rods 65, supported on brackets 66, provide sliding bearings for the blocks. By means of this construction the frames may tilt to conform to uneven ground without being drawn sidewise out of line with the runners, as the secondary bars will yield slidingly in the slots or on the rods, as the case may be. The two forms of connection are shown to better illustrate the principle of this part of my invention; but in practical use but one form will be used in any one drill, though, if desired, a similar sliding connection may be made between the principal and the secondary bars.

The seed is supplied to the runners in the customary manner from hopper 8. The fertilizer is fed from hopper 9, and the covering is effected by wheels 7.

The construction of the springs is such that elasticity is distributed throughout a comparatively great length, and consequently the pressure does not materially increase as the runners rise. This enables the grain to be deposited at an even depth in uneven ground, and the tension-regulating screws make it possible to vary the depth of deposit to suit various requirements.

The peculiar construction of the rear terminations of the runners enables the soil that is removed from the furrows below broken line Y in Fig. 14 to be ridged up above the normal line of the surface of the ground to the highest maintainable point and with the expenditure of a very small degree of force. This latter will be better understood when it is considered that, with the exception of the small rectangular furrows formed to receive the seed, there is no occasion to compress the soil laterally, but that the ridge is formed

by an oblique raising of the soil effected by scraping motion of properly-inclined surfaces. The ridges, formed as described, serve to protect the grain against frost and wind, and are 5 particularly desirable.

The weight of the forward frame, especially in drills having a large number of runners, is so great that it is necessary to use great leverage in raising it. This necessitates the 10 shortening of arm 17 to such an extent that the front frame and runners cannot be raised to the proper height with one sweep of the hand-lever. To overcome this I cause the lock-latch 23 to hold rack 16, while the hand-lever is disengaged therefrom and moved forward to engage said rack for as many additional sweeps as is necessary to raise the runners as high as desired. The same lock-latch attachment is necessary in lowering the frame 15 20 when the same has been raised to its full height. In the particular construction shown the latch is designed to be operated by foot-pressure; but it is obvious that connections may be made that will enable hand-power to be used when desired. The catch of the hand-lever is usually locked out of contact with the rack as shown in Fig. 2, and heretofore in passing over abrupt depressions, as dead furrows, the rack has been liable to swing to 25 30 such an extent that its connection with the lift-bar 18 would pass a line drawn from its axis to the pivotal point on bar 19, and so produce a dead-lock that could only be overcome with difficulty. In the present construction the extension 18^a strikes against arm 17 and prevents such disadjustment. The lift-bar, as shown, comprises two parts that embrace arm 17, and a connecting-bolt provides the stop; but it is obvious that stops 35 40 may be formed in various ways, either on the arm or on the lift-bar, and I do not therefore confine my invention to the particular stop shown and described.

The utility of the evener lies in an avoidance of side draft, enabling straight driving 45 to be easily accomplished, and in the removal of the strain from the tongue when turning the machine around, both features being desirable in drills of all sizes, and almost indispensable in the wider kinds. This arrangement can be utilized on the above-described plan for any number of horses. When for two horses only, the center pulley is attached to an extension of the main beam 20, or to the 50 tongue, and in using the device for three or five horse drills the tongue is set to one side.

The lid-fastener enables the lid to be locked open while putting in the seed and be securely closed while filled. This is desirable 55 as a provision against wind, which, when high, tends to blow the lid closed when open, and open when closed. It also acts to protect the contents of the hopper from disturbance by animals. It will be seen that the lock-lever 60 would operate on the outside of the hopper, and this change, together with obvious modi-

fications in the construction of the lock-lever and adjuncts, is intended to be included in these Letters Patent, the essential features of this part of the invention being a lock at the 70 center of the hopper or near thereto, and connections therewith accessible from the ends of the hopper.

The fertilizer-conveyer may be so adjusted that the lower end thereof will more or less 75 nearly approach the shank of the runner, so that the seed may be deposited and covered more or less deeply before the fertilizer is discharged, it usually being desirable that the fertilizer shall not come in contact with the 80 grain. After the fertilizer is deposited the press-wheels cover both it and the seed with a layer of soil firmly compressed.

Having thus described my invention, I claim as new and desire to secure by Letters Patent—

1. In combination with the runner-frame of a grain-drill, lugs projecting from the frame, a runner having a bifurcate forward termination embracing the lugs, a shaft extending through the lugs and the bifurcate end of the runner, and a spiral spring on the shaft having one end bearing against the runner and the other end against the frame, as set forth. 90

2. In combination with the runner-frame of a grain-drill, lugs projecting from the frame, a runner having a forward bifurcate termination embracing the lugs, a shaft extending through the lugs and the bifurcate end of the runner, and a compound spiral spring formed 95 of a loop of metal encircling the shaft and bearing with its loop against the runner and with its ends against the frame, as set forth. 100

3. In combination with the runner-frame of a grain-drill, lugs projecting from the frame, 105 a runner having a bifurcate forward termination embracing the lugs, a shaft extending through the lugs and the bifurcate end of the runner, a compound spiral spring formed of a loop of metal encircling the shaft and bearing 110 with its loop against the runner and with its ends against the frame, and a set-screw in the runner adapted to the loop of the spring, as set forth.

4. In combination with the runner-frame 115 of a grain-drill, a runner pivotally connected with the frame, a spring bearing on the runner, and a set-screw in the runner to regulate the tension of the spring, as set forth.

5. In grain-drills, in combination, rear 120 frames mounted on wheels and carrying a driver's seat, a front frame pivotally connected with the rear frames, means on the rear frames for raising and lowering the forward frame, runners connected with the forward frame and supporting the same when in operation, 125 springs tending to press the runners downward, and flexible connections between the rear ends of the runners and the frame forming positive stops, as set forth. 130

6. In grain-drills, in combination, a frame, a runner connected with the frame by a spring

joint, and a yielding connection between the rear end of the runner and the frame, forming a positive stop, as set forth.

7. In grain-drills, in combination, a front frame having runners attached, rear frames hinged thereto and carried on wheels, a rack pivotally supported from the rear frame and having an arm, as 17, a hand-lever mounted on the pivot of the rack and having a lock-bolt adapted to the teeth of the rack, a beam of the front frame extended rearwardly, and a connecting-bar pivoted on the end of the beam, connected pivotally with the arm of the rack, and extended above said arm to 15 form a stop, as set forth.

8. In grain-drills, in combination, a front frame with runners attached, rear frames hinged thereto and mounted on wheels, a rack supported pivotally on the rear frames and 20 connected with the forward frame, a lever mounted on the pivot of the rack, and having a bolt adapted to the teeth of the rack, and a lock-latch adapted to the teeth of the rack and held normally out of contact there- 25 with, as set forth.

9. In grain-drills, in combination, a tongue, a frame rigidly secured to the under surface of the tongue, a swinging frame pivoted vertically in the rigid frame, and a four-horse 30 yoke swung on a horizontal pivot in the

swinging frame, as and for the purpose set forth.

10. In grain-drills, in combination with the runner-shanks thereof, fertilizer-conveying tubes pivotally connected with the upper rear 35 portions of the shanks, and means for securing the tubes in various positions of adjustment, whereby soil in greater or less quantity may be made to intervene between the seed and the fertilizer, as set forth. 40

11. In grain-drills, in combination, a hopper having a hinged lid, a lock-hinge at or near the longitudinal center of the hopper, and lines connected to bolt of the lock-hinge and extended to the ends of the hopper, as set 45 forth.

12. In grain-drills, in combination, a front frame having runners, rear frames mounted on wheels and connecting pivotally with the front frame, distributing-bars slidably connected with the rear frames, and a seat supported from the weight-distributing bars, as 50 set forth.

In testimony whereof I sign my name in the presence of two subscribing witnesses.

JOHN W. RHODES.
